(57) **CLAIM**

The ornamental design for shoestring shoeps, as shown and described.

DESCRIPTION

FIG. 1 is a top, side perspective view of a shoestring shoeps, showing my new design;

FIG. 2 is a top plan view thereof;

FIG. 3 is a bottom plan view thereof;

FIG. 4 is a side elevation view thereof; and,

FIG. 5 is a front elevation view thereof.

All surfaces not shown form no part of the claimed design.
